Primary Examiner—Prabhakar Deshmukh(74) *Attorney, Agent, or Firm*—Calfee, Halter & Griswold LLP**CLAIM**

The ornamental design for a receiver pin, as shown and described.

DESCRIPTION

FIG. 1 is a perspective view of a receiver pin showing our new design;

FIG. 2 is a top view of the design shown in FIG. 1;

FIG. 3 is a side view of the design shown in FIG. 1;

FIG. 4 is a bottom view of the design shown in FIG. 1;

FIG. 5 is a back view of the design shown in FIG. 1;

FIG. 6 is a side view of the design shown in FIG. 1; and,

FIG. 7 is a front view of the design shown in FIG. 1.

The broken lines, which define the bounds of the claimed design, form no part thereof. The broken line environmental showing is for illustrative purpose only and forms no part of the claimed design.
